(57) **CLAIM**

The ornamental design for a mobile computer cart, offset base assembly, as shown and described.

DESCRIPTION

FIG. 1 is a perspective view of the mobile computer cart, offset base assembly of the invention, in which the broken lines that define the bounds of the claimed invention form no part thereof;

FIG. 2 is a front elevational view of the mobile computer cart, offset base assembly of FIG. 1;

FIG. 3 is a rear elevational view of the mobile computer cart, offset base assembly of FIG. 1;

FIG. 4 is a left side elevational view of the mobile computer cart, offset base assembly of FIG. 1;

FIG. 5 is a right side elevational view of the mobile computer cart, offset base assembly of FIG. 1;

FIG. 6 is a top view of the mobile computer cart, offset base assembly of FIG. 1; and,

FIG. 7 is a bottom view of the mobile computer cart, offset base assembly of FIG. 1.
